UNITED STATES PATENT OFFICE.

AUGUSTINE FRANK LITTLEFIELD, OF LYNN, MASSACHUSETTS.

CHANNELING-MACHINE.

SPECIFICATION forming part of Letters Patent No. 623,325, dated April 18, 1899.

Application filed January 10, 1898. Serial No. 666,163. (No model.)

To all whom it may concern:

Be it known that I, AUGUSTINE FRANK LITTLEFIELD, of Lynn, Essex county, Massachusetts, have invented an Improved Channeling-
5 Machine, of which the following is a specification, reference being had to the accompanying drawings, in which—

Figure 1 is a side elevation of a channeling-machine embodying my improvements. Fig. 1^a is a view from the side opposite to that shown in Fig. 1. Fig. 2 is a section on line 2 2 of Fig. 1. Fig. 3 is a plan view. Fig. 4 is a side elevation of the swinging frame and connected parts. Fig. 5 is a plan of the swinging frame. Fig. 6 is a side elevation of the rising frame and connected parts. Fig. 7 is a plan of the rising frame. Fig. 8 is a front elevation of the swinging frame and connected parts.

I have shown in the drawings and shall describe in this specification a channeling-knife which is vibratory or reciprocating, that being, I believe, the most useful, the knife being moved back and forth rapidly by a carrier, to the outer end of which it is secured, 25 the cutting action of the knife taking place when the knife is moving in a direction opposite to that in which the leather is being fed and the feeding action of the leather being in part accomplished while the knife is 30 making its back stroke, the movement of the leather being continuous. In this way the channel is cut by a series of short strokes of the knife. The knife is withdrawn after every 35 stroke and again forced forward against the moving leather. The practical result of this method of forming the channel is that it can be cut without heating, straining, or binding, while the tendency to "dig in," caused by variations in the density of the stock, is ob- 40 viated by the withdrawal and fresh start at every stroke, and for the same reason changes in the direction of the channel are easily made, it being easy to "pivot" in order to channel around a sharp-pointed toe part of 45 a sole.

In the drawings, A represents the frame of the machine, B the main shaft, and B' the driving-pulley on that shaft. The main shaft is carried in bearings b' b³ b⁵, and between 50 bearings b' b³ the shaft is formed as an eccentric b², and between bearings b³ b⁵ it is formed as an eccentric b⁴. (See Fig. 2.) A

fork d embraces eccentric b², the fork d being carried at the free end of an arm D', whose other end is fast to an upright pivoted shaft 55 D. The fork d is secured on arm D' by means of a tang d' and a nut d², the object of this mode of connection being to allow the shaft D to be lifted while in operation and to permit the fork to turn slightly as the arm D' 60 swings in order that the inner faces of the fork may preserve a proper relation to the surface of the eccentric-shaft, as will be obvious. The shaft D is supported at the bottom by an adjusting-screw d³ in the frame of the 65 machine and is steadied by bearings d⁴ d⁵, fast to a rising frame D². This rising frame D² carries, besides the knife-shaft D, a feed-wheel E and a presser-foot F, the feed-wheel being upon the end of a shaft e, carried in a 70 bearing in the rising frame D² and connected by a universal joint e' with a shaft e², which is driven through a pinion e³, the pinion e³ and the shaft e² being supported by a bearing a' on the frame A of the machine. The presser-foot F is fast to the frame D². At its upper end the shaft D is pressed downward by a spring d⁶, the pressure of which is regulated by a screw d⁷, the ends of the spring bearing upon collars d⁸ d⁹ upon the screw d⁷ at the head 80 of the shaft D, respectively, and the screw working in a bracket a³ on the frame of the machine. At the bottom of shaft D is a knife-carrier D³, properly formed to receive and retain the knife d¹⁰, the function of which is to 85 cut the feather-edge or shoulder upon the edge of the sole.

It will be clear that the shaft D is capable of upward movement against the force of spring d⁶, and that it may be moved in either direction upon its axis, and that at each revolution of shaft B the arm D' will be moved to and fro upon its axis through the fork d engaging the eccentric part b² of the shaft B. The pivoted shaft D will therefore be rocked and the 95 knife d¹⁰ vibrated.

Mounted upon a screw-threaded portion of shaft D are a nut d¹¹ and a check-nut d¹², the nut d¹¹ being set down upon or nearly upon the top of the rising frame D², so that any upward movement of the frame will carry with it the shaft D. The rising frame is supported upon a spring-rod G, to the upper end of which it is fast, this rod G having a capacity for up- 100

ward movement in bearings in the frame of the machine against the force of the spring g .

It will now be obvious that any variation in the thickness of the stock fed to the machine 5 (the revolving table upon which the stock is supported being carried in bearings in the frame of the machine) will, through the presser-foot F , which is fast to the rising frame D^2 , lift the rising frame and those parts carried 10 by it—namely, the feed-wheel E and the shaft D —the shaft D being forced up through nut d^{11} against the force of spring d^6 and the entire frame being forced up against the force 15 of spring g on rod G , so that as soon as the thickness has passed under the presser-foot the frame D^2 and the shaft D will be thrown down again by the springs d^6 and g . The joints and bearings of shaft e are loose in order to permit this slight upward movement 20 caused by uneven stock without undue strain or binding, and the connection between the shaft D and the eccentric b^2 on shaft B being by a fork d upward movement of the parts has no effect upon the connection.

25 The mechanism which has so far been described is related exclusively to the operation of the feed-wheel E and the shaft D , which carries the knife for cutting the "feather-edge channel," so called.

30 Upon the opposite side of the feed-wheel E from the knife-carrier D^3 and the presser-foot F is another knife-carrier, which carries the knife for cutting the channel, and a corresponding presser-foot for regulating the 35 depth of that channel. This knife-carrier, its operating-shaft, and the presser-foot are carried by a swinging frame H^2 , (see Fig. 4,) pivoted at a^2 to the frame A of the machine. This swinging frame is formed in two parts.

40 That part which is pivoted directly to the frame of the machine is shown in plan at Fig. 5, and this part carries the main shaft B , with its two eccentric portions b^2 b^4 . The swinging frame H^2 , as has been said, is pivoted at a^2 to the 45 frame A of the machine, and by this arrangement the knife-carrier H^3 , knife h^7 , and presser-foot J may be lifted whenever the rising frame D^2 is raised, the carrier, knife, and 50 presser-foot swinging upon the arc of a circle of which a^2 is the center whenever the rising frame D^2 is in rising, through screw d^{14} , tilts frame H^2 . Obviously, also, if it is not desired to lift the knife h^7 to correspond with every upward movement, however slight, of frame 55 D^2 and its knife d^{10} , by adjusting screw d^{14} down any required play within certain limits can be given to knife d^{10} without affecting knife h^7 . The tilting of swinging frame H^2 by the passage of an inequality under presser-foot J will not, obviously, in any way affect 60 the feather-edge knife d^{10} , which is carried by rising frame D^2 , because swinging frame H^2 is not fast to the rising frame, but merely projects over a part of the rising frame D^2 and 65 is thus in the path of that frame when it lifts. The connecting-bolt h^{11} merely preserves the relations of the two frames in re-

spect of displacement crosswise of the length of the frames, but permits changes of relative position in a perpendicular direction. For 70 the purpose of placing stock in the machine to be operated upon the lifting of the rising frame will raise also the swinging frame through screw d^{14} .

The working of the feather-edge knife, 75 which is operated by shaft D , by the eccentric b^2 has already been described. The eccentric b^4 works the shaft H , which carries at its lower end the knife-carrier H^3 . The connection between the shaft H and the eccentric b^4 on shaft B is made by an arm H' , pinned to shaft H and carrying a fork h , which is secured to the arm H' by a tang h' and nut h^2 , all much the same as the means employed to connect shaft D with shaft B . The shaft H 80 is carried, however, by a part H^X of the swinging frame H^2 , which part H^X is mounted upon the outer end of the frame in such a fashion as to be capable of limited lateral adjustment under the control of adjusting-screws, as will be plain from an inspection of Figs. 4, 5, and 8.

In Fig. 8 the control of part H^X is most plainly shown, the adjusting-screw being marked h^X . This adjusting-screw is held by 95 a bracket h^{XX} fast to the outer end of frame H^2 , the head of the screw being upon the outer side of the bracket and a collar fast to the screw h^X being upon the inner side of the bracket. The screw-threaded point of screw h^X enters a screw-threaded aperture in part H^X . When the adjusting-screw is turned, it will be clear that as the screw itself is held against longitudinal movement the part H^X must move according as the screw is turned. 100 By means of this lateral adjustment of part H^X the relative position of knife h^7 with regard to knife d^{10} may be altered so as to bring it to either side of knife d^{10} , as may be desired. The outer end of the main part of the 105 swinging frame is slotted to permit of the passage of the shaft H and the presser-foot J and to afford room for lateral movement of the two shafts. The arm H' carries upon its upper surface about midway of its length a 110 bracket for the adjusting-screw h^3 of the presser-foot. The adjusting-screw h^4 for the shaft H is carried by the part H^X of the swinging frame. The presser-foot is pinned to the arm H' by a set-screw, and it is also connected to the shaft H at its lower end by a bracket 115 h^5 . The knife-carrier H^3 upon the lower end of the shaft H projects to bring the knife h^7 in line with the presser-foot. It will now be clear that the revolution of shaft B will partially turn shaft H to and fro upon its axis, while it will move the presser-foot J and the knife h^7 in the arc of a circle, of which the axis of shaft H is the center; the slot h^8 in the outer 120 end of swinging frame H^2 permitting this movement of the presser-foot. The function of the springs h^9 h^{10} upon shaft H and presser-foot J is to hold the shaft H and presser-foot up against the point of the adjusting-screws 125 130 135

when the set-screws which connect the shaft and presser-foot to their operating parts are loosened to permit of perpendicular adjustment.

5 A spring-rod M is pinned to the swinging frame, (see Fig. 4,) the upper end of which passes through an aperture in a bracket a^3 on the frame of the machine, against the under side of which bracket the spring m bears, 10 while its lower end bears upon a collar m' on the spring-rod. It will be obvious that this spring tends constantly to press down the swinging frame and all that the swinging frame carries. Adjustment of the swinging 15 frame may be had by the nuts m^2 m^3 upon the spring-rod, and the tension of the spring is controlled by the collar m' .

At the right of Fig. 6 is shown an adjusting-screw d^{13} , which serves to limit the downward movement of rising frame D^2 , its point bearing against the frame of the machine. Another adjusting-screw d^{14} (see Figs. 6 and 1^a) on the rising frame bears against the under side of the swinging frame. A headed bolt h^{11} , fast to the swinging frame and passing through an aperture in the rising frame, binds the two frames together against lateral movement, while permitting a change in their relative positions perpendicularly.

30 The revolving table K, which supports the stock, is carried in a bearing k in the frame of the machine and is driven through beveled gears k' k^2 , shaft k^3 , and pinion k^4 from the crank-pinion k^5 , which drives also the feed-wheel pinion e^3 , the proportions of the pinions being such as to give the same surface speed to the table K and the feed-wheel E. The edge guide L slides in bearings in the frame of the machine and is controlled by a bell-crank lever l and spring-rod l', the spring l² of which keeps the edge guide pressed to place until retracted by the foot of the operator.

The mode of operation is as follows: The adjustment of the knives and their respective presser-feet having been determined by means of the adjusting-screws d^{13} d^{13} h^3 h^4 h^5 , the spring-rod G is first lifted by the operator against the force of its spring g. This lifts the rising frame D^2 and everything carried by that frame. It also lifts the swinging frame H^2 and everything carried by that frame through the adjusting-screw d^{14} , which bears against the bottom of the swinging frame. The sole to be channeled is then placed upon the table K, and the rod G being released the knives are pressed down upon the upper surface of the sole by the springs d^6 and m. The shaft B is then set in motion, causing the knives d^{10} and h^7 to be vibrated or reciprocated, and the crank-pinion k^5 being revolved the feed-wheel E and table K feed the stock, the feed-wheel pressing against the stock with a pressure determined by the adjustment of spring g and serving, in addition to its feeding function, the purpose of a supplementary presser-foot for both knives. Any variation in the thickness

of the stock passing under presser-foot F will lift frame D^2 , shaft D, and the knife d^{10} , which it carries, the presser-foot F being clamped to the frame D^2 . The lifting, however, will not affect the continued operation of the shaft D, for by means of the slot-and-eccentric connection (see Fig. 2) the connection of the arm D' with the shaft B is not affected. The lifting will be accomplished against the force of spring g, which will throw the frame D^2 down as soon as it is permitted to do so. Any variation in the thickness of the stock passing under the presser-foot J will lift the swinging frame H^2 , the presser-foot J being fast to that frame, against the force of spring m, which will throw frame H^2 down as soon as it is permitted to do so. Obviously the lifting of frame H^2 will not affect the operation of shaft H, which is driven by a slot-and-eccentric connection with shaft B, as is shaft D.

The adjustment of the relations of the shaft H and the carrier H^3 and the knife h^7 , which it carries, with presser-foot J and the fixing of the depth of the channel are effected by loosening the set-screw which connects the presser-foot J with the arm H'. The presser-foot may then be adjusted to any required position with regard to the carrier H^3 , and when the presser-foot is again connected to the arm both shaft H and presser-foot J, so connected to it, may be raised or lowered together by means of screw h^4 .

What I claim is—

1. In a channeling-machine, the combination of a feed-table carried by the frame of the machine; a rising frame; a feed-wheel carried by the rising frame; an arm pivoted in that rising frame and carrying a slotted piece at its end; an eccentric adapted to rotate within that slot and a knife moved by the movement of the arm, all organized and operating substantially as described. 100

2. In a channeling-machine, the combination of a revolving feed-table carried by the frame of the machine; a rising frame; a feed-wheel and a pivot-shaft carried in that frame; an arm fast to the pivot-shaft and carrying a slotted piece at its free end; an eccentric adapted to rotate within that slot and a knife secured to the pivot-shaft, all organized and operating substantially as described. 110

3. In a channeling-machine, the combination of a frame; a pivot-shaft carried in that frame and longitudinally adjustable; a knife-carrier fast to the shaft; an arm fast to the shaft; means to swing the arm and its pivot-shaft; a presser-foot detachably secured to the arm; all organized to permit adjustment between the knife-carrier and presser-foot and to swing the carrier and presser-foot together with the pivot-shaft, substantially as described. 120

4. In a channeling-machine, the combination of a feed-table and a feed-wheel; a reciprocating knife upon each side of the feed-wheel; a pivoted knife-carrier for each knife and an eccentric-and-slot connection between 130

each knife-carrier and the driving-shaft, all organized and operating substantially as described.

5. In a channeling-machine, the combination of a feed-table and a feed-wheel; moving knives upon each side of the feed-wheel; a pivoted knife-carrier for each knife; means to vary the relative horizontal and vertical position of the knife-carriers with regard to

each other, and an eccentric-and-slot connection between each knife-carrier and the driving-shaft, all organized and operating substantially as described.

AUGUSTINE FRANK LITTLEFIELD.
